[57] CLAIM

The ornamental design for a cosmetic sampler tear tab, as shown.

DESCRIPTION

FIG. 1 is a top plan view of a cosmetic sampler tear tab showing our new design;

FIG. 2 is a bottom plan view thereof;

FIG. 3 is a right side elevational view thereof, the left side elevational view being a mirror image of the right side elevational view;

FIG. 4 is a front elevational view thereof; and

FIG. 5 is a rear elevational view thereof.

This is a continuation of utility application Ser. No. 098,279 filed Sept. 18, 1987.
